UNITED STATES PATENT OFFICE

HARRY G. KAUFMAN, OF NEW YORK, N. Y.

DESIGN FOR A GEM SETTING

Application filed November 11, 1929. Serial No. 33,401. Term of patent 7 years.

To all whom it may concern:

Be it known that I, HARRY G. KAUFMAN, a citizen of the United States, residing in New York, in the county of New York and State of New York, have invented a new, original, and ornamental Design for Gem Setting, of which the following is a specification, reference being had to the accompanying drawing, forming part thereof, in which:—

Fig. 1 represents a front view of a gem setting embodying this design.

Fig. 2 is a side view of the same.

Fig. 3 is a top view of the same.

Fig. 4 is a perspective view of the same.

I claim:

The ornamental design for a gem setting as shown.

HARRY G. KAUFMAN.
